COASTER RACK

Frank J. Curran, Downers Grove, Ill.

Application October 9, 1948, Serial No. 149,060

Term of patent 14 years

(Cl. D44—24)

To all whom it may concern:

Be it known that I, Frank J. Curran, a citizen of the United States, residing in Downers Grove, county of Du Page, and State of Illinois, have invented a new, original, and ornamental Design for a Coaster Rack, of which the following is the specification, reference being made to the accompanying drawing, forming a part thereof.

Fig. 1 is a top plan view of a coaster rack, showing my new design;

Fig. 2 is a front elevational view of the same;

Fig. 3 is a bottom view of the same; and

Fig. 4 is an end elevational view of the same.

I claim:

The ornamental design for a coaster rack, as shown.

FRANK J. CURRAN.
